UNITED STATES PATENT OFFICE.

CORNELIUS S. CLARK, OF NORFOLK, VIRGINIA.

FILLER-BLOCK FOR RAILS.

1,163,214.

Specification of Letters Patent.

Patented Dec. 7, 1915.

Application filed February 11, 1915. Serial No. 7,623.

To all whom it may concern:

Be it known that I, CORNELIUS S. CLARK, a citizen of the United States, residing at Norfolk, in the county of Norfolk and State of Virginia, have invented new and useful Improvements in Filler-Blocks for Rails, of which the following is a specification.

My present invention relates to road bed construction, particularly for street railway 10 road beds, and has for its object to provide a new and improved filler block for the rail cavities.

The block which I have invented, and which I shall describe in its several forms 15 hereinafter, is designed to furnish a cheap and satisfactory filling for the rails, and further to provide a filler which will interlock with the paving blocks in such manner as to give a paving section adjacent a rail, 20 which will be so interconnected as that it will not become readily displaced under traffic, and yet which in case of needed repairs to or replacement of the rails can be readily removed.

25 In the drawings which accompany and form a part of this specification, I have illustrated several forms of my invention, all embodying the same characteristic features, and in said drawings—

30 Figure 1 is a transverse sectional view, parts being shown in elevation, of a road-bed to illustrate my new improved form of filler block. Fig. 2 is a view showing a slightly modified block. Fig. 3 is a similar view showing the block worked out in metal. Fig. 4 is a plan view of a rail joint with the tread flange cut away to show the form of block shown in Fig. 3.

35 Referring to the drawings by numerals, like numbers indicating like parts in the several views, 10 indicates a rail of any standard or desired construction, characterized, as is customary, by a bed flange, a vertical web, and a tread flange. The rail 10 will, 40 of course, be laid upon any suitable foundation, and the filler blocks which I have invented will then be utilized to fill in between the bed and tread flanges and against the vertical web.

45 Much difficulty is experienced in street railway bed construction in maintaining the paving adjacent the rails in good condition, the car traffic and vehicle traffic tending to displace these, and this naturally results in an uneven street surface. The filler blocks

which I have invented are designed to avoid this difficulty, and they comprise, as shown in Fig. 1, blocks 11 which may be of any suitable length for convenient handling and setting. The block 11 is fitted on one side to the contour of the rail cavity and has its upper end bearing against the underside of the tread flange 12, while its lower end or foot rests upon the bed flange 13 of the rail. The opposite side of the block 11 has an offset 14 at its upper end, which offset forms a seat, beneath which the paving material, such as the block 15 having an outstanding flange (which block 15 is of my invention and forms the subject matter of a pending application) may engage. At its lower end 60 the block 11 is chamfered off or inclined inwardly and downwardly as at 16 so that the grout or ballast beneath the block surface will pack heavily and closely against this 65 inclined face, and any downward pressure will tend to wedge the block 11 more closely to its seat in the rail cavity.

70 Where the block is used adjacent a rail joint box 17, as shown in Fig. 1, it will be formed as there shown with a straight or inclined face at its bottom, and the offset 18 will engage a complementary recess 19 on the joint box as shown.

75 Where the block is used over a fish plate 85 it will be constructed similar to the block first described, except that in adapting it to the fish plate the inner face of the block 20, as shown in Fig. 2, will be channeled or grooved or recessed as at 21, so as to span 90 the bolt heads and provide bearing lugs 22 which will rest directly against the fish plate.

85 In Fig. 3 I have disclosed my invention as worked out in metal, and instead of filling 95 the rail cavity solidly with the block I provide the web 23 which engages at its top beneath the tread flange of the rail, and has at its bottom the foot 24 resting upon the bed flange, the web at its lower portion being 100 inclined inwardly and downwardly to the foot to give the wedging face referred to in connection with the wooden block. In order to sustain the web against severe crushing 105 strains I preferably provide it with a horizontally projecting strut which, as shown in Fig. 3, takes its bearing against the web of the rail and resists inward strains.

110 It will be understood that so far as design is concerned these blocks will be varied in

shape to meet the needs of the work, and such variations I regard as within the purview of my invention.

I claim:-

- 5 1. A filler block for rails having a bed flange engaging foot, a tread flange engaging top, and provided with an offset forming an overhanging shoulder on its front face said shoulder being adapted to engage on a seat formed by an offset in an adjacent paving block to hold it against vertical movement.
- 10 2. A filler block for rails having a bed flange engaging foot, a tread flange engaging top, and a front face inclined inwardly toward the rail and downwardly, whereby the said block will be forced to its seat between the flanges.
- 15 3. A filler block for rails having a bed flange engaging foot, and a tread flange engaging top, the front face of said block being inclined inwardly and downwardly at its lower part, the upper part of said block having an offset portion to engage in

adjacent paving block and maintain the 25 same in fixed position.

4. A filler block for rails having a bed flange engaging foot, and a tread flange engaging top, said block having in its rear wall a receiving cavity to give clearance for 30 the bolt heads, and a brace or strut extending rearwardly from said block to support it against horizontal strains.

5. A filler block for rails comprising a web extending from the tread flange to the 35 bed flange and engaging at its top and bottom edges said flanges, said web being inclined inwardly toward the rail and downwardly whereby the said block will be forced 40 to its seat between the flanges.

In testimony whereof I have hereunto set my hand in presence of two subscribing witnesses.

CORNELIUS S. CLARK.
